UNITED STATES PATENT OFFICE

2,433,745

BOAT HULL CONSTRUCTION

Herbert Ditchburn, Trenton, Ontario, Canada

Application February 9, 1945, Serial No. 577,032

2 Claims. (Cl. 9—6)

1

This invention relates to improvements in steel boat construction and particularly a welded hull structure for speed boats, flying boats, aeroplanes, military and other pontoons and commercial or work boats, and the principal object of the invention is to produce a hull structure with an extraordinarily high strength, weight ratio at extremely low cost.

A further object is to devise a form of construction which will obviate the necessity of providing moulds or setting up jigs and other expensive equipment usually required for fabricating steel in the conventional manner.

A still further object is to devise a construction which will enable the placing of additional strengthening elements at various places in a hull structure without requiring special patterns and the shaping of transverse frames.

The principal feature of the invention consists in forming the longitudinal keel, chine and gunwale members of the boat of continuous lengths of tubing and spacing and rigidly connecting said longitudinal members with rigid struts having their ends abutting and securely welded to the longitudinal members, the outer shell plates of the hull being rigidly secured to said longitudinal tubes and transverse strut members.

A further feature of the invention consists in the novel arrangement of spaced longitudinal members for supporting the shell plates between the angularly disposed struts, whereby dishing or buckling of the plates will be prevented.

In the accompanying drawings,

Figure 1 is a half plan view of the frame of a speed boat constructed in accordance with this invention.

Figure 2 is a side elevational view of the boat hull illustrated in Figure 1 showing the shell plates partly broken away at the bow end and showing the arrangement of the side struts in dotted lines.

Figure 3 is a half front elevational view of a boat hull frame structure showing a half sectional and rear end view.

Figure 4 is an enlarged horizontal sectional view taken through the stem portion of a boat frame constructed in accordance with this invention.

Figure 5 is an enlarged half transverse broken section taken on the line 5—5 of Figure 2.

Figure 6 is an elevational detail of one of the side strut members as shown in the assembly of Figure 5.

Figure 7 is a broken longitudinal plan section

2

of a length of a boat hull taken on the line 7—7 of Figure 5.

Figure 8 is a plan detail showing two different forms of metal longitudinal shell plate supports.

Figure 9 is a half sectional end elevational view showing a modified form of tubular hull construction particularly adapted for work boats.

In the manufacture of speed boats, flying boats and aeroplane hulls it has been customary to construct rigid transverse frames to be located at various points throughout the length of the hull and to which the longitudinal planking is secured. Such construction is expensive and in order to have sufficient strength to stand the impact blows to which it is subjected in rough waters at high speeds the weight ratio is undesirably high.

The present invention contemplates the use of light but strong steel tubing to form the major longitudinal members of the boat structure and such structures are rigidly joined by light but strong metal struts to which an outer shell of light steel plating is rigidly secured by being welded at numerous points.

In carrying the present invention into effect the main longitudinal members of the boat structure, such as the keel, the chine and the gunwale, are formed with steel tubes bent to the desired shape. These tubular members are supported temporarily by suitable jigs or forms and the tubular keel 1 and the tubular chine 2 are connected together by transverse strut bars 3, the ends of said bars being cut on the arc of a circle to fit snugly to the circumference of the tubular keel and chine, it being only necessary to cut these strut members different lengths in accordance with their position in the structure.

A preferred form of structure for the struts 3 is that of a light steel T-bar, the web 4 of which is formed with the part circular notched ends 5. When these strut bars are inserted between the longitudinal tubular bars with the flange portion resting upon the curved perimeters of the tubes and the notched ends engaging the tube surfaces they are secured in position by welding, the ends of the flanges 6 being welded lengthwise of the tubes and the notched webs being welded continuously or partially around the circumference of the tubes.

In the forming of the keel it is preferable that the upwardly curved stem portion 7 is partially flattened into an oval shape so that it will present a narrow edge forward to act as a cutwater 8. The ends of the chinetubes can easily be fitted to the side surfaces of the stem 7 and welded.

The gunwale 9 after being properly shaped is supported in position above the chine and pre-cut lengths of struts 10, similar to the struts 3, are placed in position.

It will be noted that both in the placing of the chine relative to the keel and of the gunwale relative to the chine the notched ends of the struts will fit snugly to the circular perimeter of the longitudinal tubes irrespective of the angularity of the struts, consequently no special fitting will be required except that the struts be cut the proper length.

The struts fitted between the chine and the gunwale are welded into position in a similar manner to the bottom struts and where the forward end of the boat is to be covered with a decking a centre tube 11 secured at the forward end to the stem of the keel is connected with the gunwale by struts 12 similar to the struts 10 and 3.

With the construction described a very light and very rigid framework is produced and on this framework is placed the thin steel sheets which are to form the shell. These sheets will be laid upon the transversely extending edges of the webs of the bottom and side struts with their longitudinal edges engaging the transverse curvature of the longitudinal tubes and the straight right angularly sheared edges will thus present a V-groove along their contact with the longitudinal tubes to accommodate the welding metal.

It will be seen that the rounded surface of the tubes form a neat rounded corner between the plates where such may be desired but of course if it is desired to have a sharp angled corner along the chine line the shell plates can be made to extend beyond the curved surface of the tubes so that the side and bottom plates will meet and the meeting edges can be welded together and the plates themselves can be welded from the inside of the structure to the periphery of the tubes.

It will be appreciated that the shell plates can be cut the required shape to be bent to fit to the frame and to be welded in position without requiring to be specially formed by dies.

Where the ends of plates abut they can be located to form a seam in alignment with one of the struts and the abutting edges can be scarfed and the weld can be made to unite the plates securely to the strut and to be joined together in the one operation, such a joint being illustrated in Figure 7 of the drawings as indicated by the numeral 13.

In order that the thin sheet metal of the shell shall retain its contours between the transverse strut members, longitudinal supporting bars 14 may be arranged at spaced intervals to extend longitudinally between adjacent struts, and where the T-shaped strut bars are used the ends of the bars 14 are placed against the head flanges with their ends abutting the webs 4 of said struts. These bars can be held in spaced positions by wood screws 15, or they may be secured by bolts 16 which may extend through the outer shell, as illustrated in Figure 7. The bars 14 may be of wood or any light, strong material.

It will be seen that the side wall struts between the gunwale and the chine may be placed in any desirable arrangement and they will be offset in any desirable manner from the transversely arranged bottom struts, and such struts may be placed as closely together as desired in any particular position of the boat to support the engine or any other structure. In fact, as will be read-

ily appreciated the structure is extremely flexible as to the particular placing of struts.

In place of the wooden longitudinal support bars it may be found desirable to use metal strips and these may be placed in straight line arrangement between the webs of the struts, as illustrated by the numeral 17 in Figure 8, or, such strips may be waved as shown at 18 and the edges may be tacked by welding at any desirable number of spots along their edges to the inner surface of the shell plate.

A boat hull structure such as described will be very strong for comparatively light weight. It will be simple to manufacture, requiring no special machinery or expensive forming tools.

The tubular structure can be utilized to advantage as fluid carriers if desired. A keel structure, for instance, may be effectively perforated at points and serve as a bilge conduit and either chine or gunwale structures may be used for conveying fuel from tanks to engines.

A structure such as described will lend itself very readily to the inclusion of fuel tanks as part of the structure as they may be welded in position attached to the transverse struts and they will add strength to the structure.

In the form of boat illustrated in the half section elevation, Figure 9, the series of shaped longitudinal tubes extending from keel to gunwale are spaced apart by strut members similar to those described, that is to say, the struts are cut to length by cutting out a part-circular notch on the end which fits the tubular longitudinal members. These and the number of longitudinal tubes are regulated entirely by the weight and strength of boat required.

In the use of steel hulls such as herein described it will be understood that boats can be made practically unsinkable by welding in watertight bulkheads.

It will also be understood that steel hulls will withstand heavier impact shocks than wood hulls and will not be subject to shattering and may be easily reshaped or repaired if bent or damaged.

It will also be understood that while reference has been made herein to the structure being of steel, where extremely light-weight boats are required other light-weight metals or alloys can be used.

With a structure such as described it will be possible to fabricate boats directly in the locality where they are to be used by the use of the simple forms of tools with which such construction is possible and extremely serviceable boats are made available at minimum cost.

What I claim as my invention is:

1. A metal boat hull comprising continuous longitudinal keel, chine and gunwale, of tubes bent to form, struts formed of bars of T-shaped cross section arranged transversely between said longitudinal tubes having their web ends cut to fit the perimeter of said tubes with their flange ends overlapping and engaging the longitudinal surface of the tubes, said flanges and cut web ends being welded to the perimeter of said tubes, metal sheets welded to said longitudinal tubes and transverse struts, and means abutting said struts and reinforcing said metal sheets between said struts.

2. A metal boat hull comprising continuous longitudinal tubular keel, chine and gunwale members, T-shaped struts having their web ends notched to fit the periphery of the tubular members and to extend therebetween, the flanges of said struts overlapping and bearing lengthwise

of and being welded to said longitudinal tubes the notched ends of the webs of said struts being welded to said tubes, metal plates having their longitudinal edges square-cut and meeting the rounded perimeter of said longitudinal tubes and having the V-notch formed therebetween closed with a weld, said plates being welded to the supporting edges of the webs of said struts between said longitudinal tubes, and longitudinal bars spaced apart fitted between the webs of said transverse struts and rigidly secured between the flanges thereof and the outer plates.

HERBERT DITCHBURN.
